UNITED STATES PATENT OFFICE.

FREDERIC J. MACISAAC, OF NEW YORK, N. Y.

COFFER-DAM.

1,075,361.

Specification of Letters Patent.

Patented Oct. 14, 1913.

Application filed June 26, 1913. Serial No. 775,831.

To all whom it may concern:

Be it known that I, FREDERIC J. MACISAAC, a citizen of the United States, and a resident of Richmond Hill, New York city, 5 county of Queens, State of New York, have invented certain new and useful Improvements in Cofferdams, of which the following is a specification.

My invention relates to improvements in 10 cofferdams.

The main object of the invention is to provide an improved construction of cofferdam which is especially adapted for large work and in places where the depth is great. 15 More specifically, I provide a structure which is not only easily and cheaply assembled and put in place, but which has great strength and rigidity. In the form shown, the walls of the cofferdam are made of steel 20 sheeting suitably interlocked and braced below the water line so that bulging or kicking out at toe of the sheeting, a trouble common to deep dams, is prevented.

Further objects, features and advantages 25 will more clearly appear from the detailed description given below taken in connection with the accompanying drawings which form a part of this specification.

In the drawings, Figure 1 is a plan view 30 illustrating the cofferdam embodying my invention in one form; Fig. 2 is an enlarged sketch taken on the line II—II of Fig. 1; Fig. 3 is a detail plan taken on the line III—III of Fig. 2; Fig. 4 is a perspective 35 showing the plates which are adapted to close the slots in the sheeting at the parts where the tension members do not pass therethrough. Fig. 5 is an enlarged detail vertical section showing the construction 40 where the tension members pass through the walls of sheeting; Fig. 6 is a transverse section taken on the line VI—VI of Fig. 2; Fig. 7 is a transverse section taken on the line VII—VII of Fig. 2; and Fig. 8 is 45 a transverse section taken on the line VIII—VIII of Fig. 5.

Referring to the drawings, 1 and 2 represent the inner and outer walls respectively, of the cofferdam. These walls are made up 50 of vertical steel sheets 3, provided on their

vertical edges with interlocking portions 4, so that the adjacent sheets may be interlocked with one another, as clearly illustrated in Figs. 3 and 8.

Some of the sheets of each wall are split 55 vertically, as at 5, so as to provide a vertical slot between the two parts thereof. Where these sheets extend down into the mud the two split halves are secured together by means of a plate 6 bolted to each half at 7 60 (see Fig. 6). After the inner and outer walls of the cofferdam have been put in place in this manner with certain of the sheets 3 split as described, the tension members 8 each consisting of an upper horizontal strip 9 and a lower horizontal strip 10 connected together by means of a plurality of bracing members 11, are dropped down between the inner and outer walls 1 and 2, in the slots 5, with the ends of 70 the tension members projecting through the slots, as clearly shown in the drawings. On the ends of each horizontal strip 9 and 10, are bolted uprights 12, and between the upper ends of these uprights and the outside of the walls 1 and 2, are placed horizontal transverse members 13 carried by the tension members 9 and 10. These transverse members abut against the interlocking joints 4 of the steel sheeting on the outside of the walls on one side of the transverse members 13, while on the other side they abut against the upright members 12. When dropping these tension members 8 into place the vertical slot between the members 9 and 10 is closed by means of members 14 comprising two plates, one on the inside and one on the outside of the wall, which plates are secured together by bolts 15, the bolts passing through the vertical slot at 5. 80 Ordinarily the first or lower layer of tension members 8 are dropped down until they rest upon the bottom of the body of water, although if desired they may be sunk to some distance below the bottom. After these 85 are put in place further members comprising plates 16 and 17 held together by bolts 18 are dropped down the slots on top of the lower row of tension members 8, as clearly shown in Fig. 2. Thereupon, another row 95 100

of tension members 8 are dropped down the vertical slots 5 in the same manner, then another set of plates covering the slots, etc., until the top of the water is reached. I 5 also provide a plurality of braces 19 extending between the lower end of the outer wall 2 and the upper end of the inner wall 1, which aid in preventing the outer wall from being pulled out in case the side of 10 the cofferdam should receive a blow, as from a scow or other boat. Also, I place above the transverse members 13 adjacent the outer wall 2, at the top, horizontal members 20 which are rigidly secured to the sheet 3 15 by means of bolts 21, so that in case the outer wall should receive any blow there would be no danger of the upper tension members 8 being shoved up and out of the slots in the walls.

20 In use the structure is put in place as described, and the space between the walls 1 and 2 is filled with soft mud and slush, the top of the same usually constituting a puddle. After being carefully put in place the 25 water on the inside of the cofferdam may then be pumped out in the usual manner.

By splitting some of the sheets 3 (in the form shown I have split substantially each alternate sheet of the walls) a simple and 30 convenient arrangement is formed whereby the tension bracing members 8 may be easily dropped in place from the top. It will be understood, however, that other arrangements by which vertical slots extending 35 downwardly from the top of the walls are provided, may be used. Also the arrangement of plates, as shown in Fig. 4, forms a simple means for closing up the vertical slots at points other than where the tension 40 members pass therethrough. In the arrangement shown, the vertical slots at 5 are cut in the metal sheets between adjacent interlocking joints and transverse members 13 bear against the joints, thus forming an efficient 45 arrangement for bracing the whole structure, and the plates 14, 16 and 17 not only form an efficient means for closing up the slots, but also properly space the tension members at different heights, so that the two 50 walls are rigidly connected from top to bottom.

Although I have described my improvements in great detail and with respect to one particular form thereof, nevertheless I 55 do not desire to be limited to such details except as clearly pointed out in the appended claims, since many changes and modifications may well be made without departing from the spirit and scope of my invention in 60 its broader aspects.

Having fully and clearly described my improvements, what I claim as new and desire to secure by Letters Patent, is:

1. A cofferdam comprising inner and outer

walls composed of interlocking metal sheets, 65 some of the sheets of both walls having vertical slots cut therein between adjacent interlocking joints, and tension members extending between the inner and outer walls and through the slots in said walls. 70

2. A cofferdam comprising inner and outer walls each composed of vertical sheets suitably joined together, some of the sheets of both walls having vertical slots therein between the joints, and tension members extending between the inner and outer walls and through the slots therein for bracing 75 the walls.

3. A cofferdam comprising inner and outer walls each composed of vertical sheets suitably joined together, some of the sheets of both walls having vertical slots therein between the joints, and tension members extending between the inner and outer walls and through the slots therein for bracing 80 the walls, said tension members carrying transverse members for engaging the sheets on the outside thereof.

4. A cofferdam comprising inner and outer walls each composed of vertical sheets suitably joined together, some of the sheets of both walls having vertical slots therein between the joints, and tension members extending between the inner and outer walls and through the slots therein for bracing 85 the walls, said tension members carrying transverse members for engaging the sheets on the outside thereof, and said transverse members being sufficiently long to extend over the joints adjacent the slots through 90 which the corresponding tension members pass.

5. A cofferdam comprising inner and outer walls composed of interlocking metal sheets, some of the sheets of both walls having vertical slots cut therein between adjacent interlocking joints, and tension members extending between the inner and outer walls and through the slots in said walls, said tension members carrying transverse members 105 for engaging the sheets on the outside thereof, and said transverse members being sufficiently long to extend over the joints adjacent the slots through 110 which the corresponding tension members pass. 115

6. A cofferdam comprising inner and outer walls each composed of vertical sheets suitably joined together, some of the sheets of both walls having vertical slots therein between the joints, tension members extending 120 between the inner and outer walls and through the slots therein for bracing the walls, and plates for covering said slots at points other than where the tension members pass therethrough.

7. A cofferdam comprising inner and outer walls each composed of vertical sheets suitably joined together, some of the sheets of

both walls having vertical slots therein between the joints, tension members extending between the inner and outer walls and through the slots therein for bracing the walls, and plates for covering said slots at points other than where the tension members pass therethrough, said plates comprising members on both sides of the wall and bolts passing through the slots for connecting said members.

8. A cofferdam comprising inner and outer walls each composed of vertical sheets, said walls having vertical slots therein extending downwardly from the top of the walls, tension members extending between the inner and outer walls and through the slots therein for bracing the walls, and plates for covering said slots at points other than where the tension members pass therethrough, said plates comprising members on both sides of the wall and bolts passing through the slots for connecting said members.

9. A cofferdam comprising inner and outer walls each composed of vertical sheets, said walls having vertical slots therein extending downwardly from the top of the walls, and tension members extending between the inner and outer walls and through the slots therein for bracing the walls, each of said tension members comprising a plurality of horizontal strips connected together by means of a plurality of bracing members.

35 10. A cofferdam comprising inner and outer walls each composed of vertical sheets suitably joined together, some of the sheets of both walls having vertical slots therein between the joints, and tension members extending between the inner and outer walls and through the slots therein for bracing the walls, each of said tension members comprising a plurality of horizontal strips connected together by means of a plurality of bracing members.

45 11. A cofferdam comprising inner and outer walls composed of interlocking metal sheets, some of the sheets of both walls having vertical slots cut therein between adjacent interlocking joints, and tension members extending between the inner and outer walls and through the slots in said walls, each of said tension members comprising a plurality of horizontal strips connected together by means of a plurality of bracing members, said tension members carrying transverse members for engaging the sheets on the outside thereof, and said transverse members being sufficiently long to extend over the joints adjacent the slots through which the corresponding tension members pass.

60 12. A cofferdam comprising inner and outer walls each composed of vertical sheets,

said walls having vertical slots therein extending downwardly from the top of the walls, tension members extending between the inner and outer walls and through the slots therein for bracing the walls, and a plurality of braces extending between the lower end of the outer wall and the upper end of the inner wall.

13. A cofferdam comprising inner and outer walls each composed of vertical sheets suitably joined together, some of the sheets of both walls having vertical slots therein between the joints, tension members extending between the inner and outer walls and through the slots therein for bracing the walls, said tension members carrying transverse members for engaging the sheets on the outside thereof, and a plurality of braces extending between the lower end of the outer wall and the upper end of the inner wall.

85 14. A cofferdam comprising inner and outer walls each composed of vertical sheets, said walls having vertical slots therein extending downwardly from the top of the walls, tension members extending between the inner and outer walls and through the slots therein for bracing the walls and spaced at different heights, and means for preventing the upper tension members from being pushed out of the slots in the outer wall.

15. A cofferdam comprising inner and outer walls each composed of vertical sheets suitably joined together, some of the sheets of both walls having vertical slots therein between the joints, tension members extending between the inner and outer walls and through the slots therein for bracing the walls and spaced at different heights, means for preventing the upper tension members from being pushed out of the slots in the outer wall, and plates for covering said slots at points other than where the tension members pass therethrough.

110 16. A cofferdam comprising inner and outer walls each composed of vertical sheets, said walls having vertical slots therein extending downwardly from the top of the walls, and tension members dropped down said slots to different heights, and extending between the walls to brace the same.

17. A cofferdam comprising inner and outer walls each composed of vertical sheets, said walls having vertical slots therein extending downwardly from the top of the walls, tension members dropped down said slots extending between the walls to brace the same, said tension members carrying transverse members for engaging the sheets on the outside thereof and spaced at different heights, and means for preventing the upper tension members from being pushed out of the slots in the outer wall.

18. A cofferdam comprising inner and outer walls composed of vertical metal sheets, said walls having vertical slots therein, and tension members dropped down said 5 slots and extending between the inner and outer walls to brace the same, for holding the walls in proper spaced relation.

In testimony whereof, I have signed my name to this specification, in the presence of two subscribing witnesses.

FREDERIC J. MacISAAC.
